United States Patent Office

Des. 208,720
Patented Sept. 26, 1967

208,720

KEY HOLDER

Norman Burkhardt, Glenhead, N.Y., assignor to Jarco Metal Products Corp., Westbury, N.Y., a corporation of New York

Filed Oct. 3, 1966, Ser. No. 4,151

Term of patent 14 years

(Cl. D50—4)

FIG. 1

FIG. 2

FIG. 3

FIG. 4

FIG. 5

FIG. 6

FIG. 7

FIGURE 1 is a top perspective view of a key holder showing my new design;

FIGURE 2 is a top plan view thereof;

FIGURE 3 is a side elevational view thereof;

FIGURE 4 is a rear elevational view thereof;

FIGURE 5 is the other side elevational view thereof;

FIGURE 6 is a front elevational view thereof; and

FIGURE 7 is a bottom plan view thereof.

The dominant portions of my design reside in those portions shown in full lines.

I claim:

The ornamental design for a key holder, as shown and described.
